US00D561487S

(12) **United States Design Patent** (10) **Patent No.:** **US D561,487 S**
Schweikarth et al. (45) **Date of Patent:** **** Feb. 12, 2008**

(54) **BENCH**

(75) Inventors: **Derek Schweikarth**, Celestine, IN (US); **Mark Wahl**, Boonville, IN (US); **Gary Meredith, Sr.**, Dale, IN (US); **Meghan Smith**, Jasper, IN (US); **Paula Schmidt**, Jasper, IN (US); **Greg Daily**, Jasper, IN (US)

(73) Assignee: **Kimball International, Inc.**, Jasper, IN (US)

(**) Term: **14 Years**

(21) Appl. No.: **29/279,590**

(22) Filed: **May 3, 2007**

(51) LOC (8) Cl. **06-01**

(52) U.S. Cl. **D6/381**

(58) Field of Classification Search D6/349-353, D6/355, 364, 484, 334, 500-502; 297/258.1, 297/259.1, 440.12, 445.1, 451.4, 461-462, 297/187

See application file for complete search history.
